US00D981791S

(12) **United States Design Patent** (10) **Patent No.:** **US D981,791 S**
Burns et al. (45) **Date of Patent:** **** Mar. 28, 2023**

(54) **BOWL**

(71) Applicant: **Lifetime Brands, Inc.**, Garden City, NY (US)

(72) Inventors: **Clay Allen Burns**, New York, NY (US); **Mario Quintana Serrahima**, Barcelona (ES)

(73) Assignee: **Lifetime Brands, Inc.**, Garden City, NY (US)

(**) Term: **15 Years**

(21) Appl. No.: **29/770,956**

(22) Filed: **Feb. 18, 2021**

(51) **LOC (14) Cl.** **07-01**

(52) **U.S. Cl.**

USPC **D7/584**

(58) **Field of Classification Search**

USPC D7/354, 393, 396, 500, 538, 540–543,

(57) **CLAIM**

The ornamental design for a bowl, as shown and described.

DESCRIPTION

FIG. 1 is a top perspective view of the bowl.

FIG. 2 is a bottom perspective view of the bowl of FIG. 1.

FIG. 3 is a first side elevation view of the bowl of FIG. 1.

FIG. 4 is a second side elevation view of the bowl of FIG. 1.

FIG. 5 is a third side elevation view of the bowl of FIG. 1.

FIG. 6 is a fourth side elevation view of the bowl of FIG. 1.

FIG. 7 is a top plan view of the bowl of FIG. 1; and,

FIG. 8 is a bottom plan view of the bowl of FIG. 1.

The evenly dotted broken lines in the figures illustrate portions of the bowl and form no part of the claimed design. The dash-dot-dash broken lines in the figures represent boundaries of the claim and form no part of the claimed design.

1 Claim, 8 Drawing Sheets
